UNITED STATES PATENT OFFICE.

JOSEPH L. JAFFE AND FREDERICK WENING, OF CLEVELAND, OHIO; SAID FREDERICK WENING ASSIGNOR TO SAID JOSEPH L. JAFFE, OF CLEVELAND, OHIO.

LIGHTING FIXTURE.

Application filed December 2, 1922. Serial No. 604,463

The present invention relates to lighting fixtures and more particularly to means for securing a globe or shade in such fixture. Thus, the present invention provides means for securing and holding a globe or the like, which means are normally outside of the holder so as to permit the easy insertion of such globe, and which are movable into globe holding position by the insertion of the globe itself. Means are also provided for locking the globe holding means in the holding position and at the same time forming a dirt-proof enclosure and concealing the holding means. To the accomplishment of the foregoing and related ends, said invention, then, consists of the means hereinafter fully described and particularly pointed out in the claims.

The annexed drawing and the following description set forth in detail certain mechanism embodying the invention, such disclosed means constituting, however, but one of various mechanical forms in which the principle of the invention may be used.

In said annexed drawing:

Fig. 1 is a central vertical section through our fixture; Fig. 2 is a sectional view above the holding elements with parts in section as indicated by the line 2—2 of Fig. 1; Fig. 3 is a perspective view of a portion of the holder showing the double slots that form a detail feature; Fig. 4 is a perspective view of a portion of the holder showing one clip in its globe holding position in the slots; Fig. 5 is a perspective view of one of the clips; and Figs. 6 and 7 are vertical sections through a clip showing the same in its normal and globe holding positions, respectively.

The present fixture comprises a holder 1 of usual bell-shaped form having a top portion in which a socket, not shown, is usually mounted, and this holder is provided near the bottom with an outwardly extending or horizontal flange 2 and a depending flange or skirt 3 with a rolled lower edge 4, the inrolled edge 5 of the head being spaced slightly from the skirt 3 to form an annular groove 6.

At the angle between the skirt and flange are a series of slots 7 and a second series of slots 8 are formed in the skirt below the slots 7, forming in effect double slots which are separated by a cross bar 9 which is inset from the plane of the skirt. Three such double slots are illustrated, these being equally spaced about the skirt, but the number and size of the slots will depend largely upon the

size of the fixture and the weight of the globe to be supported.

The globe holding means proper comprise a series of clips 10 mounted in such double slots. Each clip is a strap bent at an angle and having one leg 11 passed through the upper slot 7 of each double slot, the clip thus resting on the cross bar and being balanced thereon. This leg 11 extends straight for a distance equal to the length of the flange 2 and is then bent upwardly for its end portion 12. The depending leg 13 of the clip has a short portion 14 at right angles to the leg 11 and this portion fits against the outer surface of the cross bar and is of the same thickness as the skirt so as to be flush therewith, as best shown in Fig. 7. The lower part 15 of the leg 13 forms the globe engaging means and is bent outwardly and into a loop so as to provide a resilient globe engaging portion.

These clips are so formed that the leg 11 over-balances the leg 13, so as to normally maintain the clip in the position shown in Fig. 6 with the loop 15 substantially flush with the skirt, that is with none of the leg 13 lying within the interior of the skirt. The leg 11 thus rests on the cross bar and extends inwardly into the holder and angles away from the horizontal flange 2. This leg 11 is thus in the normal path of the globe 20 which has the usual curved upper lip 21. When the globe is inserted in the holder, the upper edge of the lip strikes the legs 11 moving them up against the flange 2 and thus pivoting the clips to bring the loops into the concave curve of the globe.

To secure the clips in this globe holding position the holder is provided with a locking ring or band 22, comprising a horizontal or inwardly extending flange 23 having a central aperture, and having a depending vertical flange 24. The ring is adapted to fit over the central portion of the holder with the flange 23 flat against the flange 2, while the depending flange 24 fits snugly around the skirt 3, as shown in Fig. 7, and extends down into groove 6 formed in the rolled lower edge of the skirt, thus concealing the lower edge of the locking ring. The inner edge of the horizontal flange 23 fits snugly against the vertically rising cylindrical portion 25 of the holder and therefore completely conceals the globe holding means and at the same time, looks to be an integral portion of the holder.

This locking ring is readily movable up

and down to secure and release the globe and forms a joint which is substantially dirt proof. As shown, it is provided with a rolled bead 26 near the upper edge of the flange 24, such bead constituting convenient means for manipulating ring and being incidentally ornamental in effect, as well. The looped ends of the clips are sufficiently resilient to allow for small differences in the size of the lip found in globes and shades as commercially manufactured, and of course the angle between the legs of such clips may be readily changed to suit different globe sizes.

The entire device is simple to construct and to assemble and no holding means show on the outside, the locking ring completely covering the clips and slots and fitting snugly with its lower edge in the bead so as to give the appearance of a unitary structure.

Other modes of applying the principle of our invention may be employed instead of the one explained, change being made as regards the mechanism herein disclosed, provided the means stated by any of the following claims or the equivalent of such stated means be employed.

We therefore particularly point out and distinctly claim as our invention:-

1. In a lighting fixture, the combination of a holder having a cylindrical portion and a flange adapted to receive a globe, a plurality of globe holding elements pivotally connected to said holder, and means for excluding foreign matter and for concealing said elements, said means comprising an annular locking member having an inwardly extending flange axially slidable on the cylindrical portion of said holder and a depending flange to engage and cover entirely over said locking elements for retaining the same in their respective locking positions, said locking elements for retaining the same in their respective locking positions.

2. In a lighting fixture, the combination of a holder provided near the bottom with a horizontal flange and a globe-receiving flange depending therefrom, said flanges provided adjacent the angle therebetween with a series of double slots, a series of locking clips comprising angled straps mounted to extend through the upper slots and balanced so as to have their lower ends normally hanging substantially flush with said depending flange but being movable inwardly, by contact with the upper edge of the globe, into globe-holding position, and a locking ring adapted to fit over said depending flange to secure said clips in their globe-holding position.

3. In a lighting fixture, the combination of a holder provided near the bottom with a horizontal flange and a globe-receiving flange depending therefrom, said flanges being provided adjacent the angle therebetween with a series of double slots, a series of locking

clips comprising angled straps mounted to extend through the upper slots and balanced so as to have their lower ends normally hanging substantially flush with said depending flange but being movable inside of the plane thereof, by contact with the upper edge of the globe, into globe-holding position, and a locking ring comprising a horizontal flange with a central aperture adapted to fit snugly around said depending flange to secure said locking clips in their globe-holding position.

4. In a lighting fixture, the combination of a holder provided near the bottom with an outwardly extending flange and a globe-receiving flange depending therefrom and having a rolled lower edge, said flanges being provided with a series of double slots adjacent the angle therebetween and the cross-bars between slots being inset, locking clips comprising angled straps having resilient lower ends, said clips being inserted through the upper slots and being balanced on said cross-bars so as normally to hang with their lower ends flush with said depending flange but being adapted to be moved inwardly, by contact with the upper edge of the globe, to engage with the curved lip of said globe, and a locking ring comprising a vertical flange and an inwardly extending flange with a central opening, said ring fitting over said outwardly extending flange and said depending flange snugly to form a dirt-proof holder and to secure said clips in their globe-holding position.

5. In a lighting fixture, the combination of a holder provided near the bottom with an outwardly extending flange and a globe-receiving flange depending therefrom and having a rolled lower edge, said flanges being provided with a series of double slots adjacent the angle therebetween, the cross-bars between slots being inset, locking clips comprising angled straps having resilient lower ends, said clips being inserted through the upper slots and being balanced on said cross-bars so as normally to hang with their lower ends substantially flush with said depending flange but being adapted to be moved inwardly, by contact with the upper edge of the globe, to engage with the curved lip of said globe, and a locking ring comprising a vertical flange and an inwardly extending flange with a central opening, said ring fitting over said outwardly extending flange and said depending flange snugly and extending into said rolled edge of said flange to conceal said globe-holding means and to form a dirt-proof holder and to secure said clips in their globe-holding position.

Signed by us, this 29th day of November, 1922.

JOSEPH L. JAFFE.
FREDERICK WENING.
